Des. 193,714
Patented Oct. 2, 1962

193,714

COMBINED TELEPHONE AMPLIFIER AND RADIO RECEIVER

Joseph Rector, 225 W. 86th St., New York, N.Y.

Filed Dec. 12, 1960, Ser. No. 63,189

Term of patent 14 years

(Cl. D26—14)

FIG. 1.

FIG. 2.

Fig. 3.

Fig. 4.

FIG. 5.

FIG. 6.

FIG. 1 is a perspective view of a combined telephone amplifier and radio receiver, showing my new design;

FIG. 2 is a front elevational view thereof;

FIG. 3 is a rear view thereof;

FIG. 4 is a top plan view thereof with the control door closed;

FIG. 5 is a bottom plan view thereof; and

FIG. 6 is a side elevational view thereof.

I claim:

The ornamental design for a combined telephone amplifier and radio receiver, substantially as shown.
